UNITED STATES PATENT OFFICE

92,674

DESIGN FOR A DIAMOND WEDDING RING

L Lee Pandres, Dallas, Tex.

Application March 26, 1934, Serial No. 51,175

Term of patent 7 years

To all whom it may concern:

Be it known that I, L LEE PANDRES, a citizen of the United States, residing at Dallas, in the county of Dallas and State of Texas, have invented a new, original, and ornamental Design for a certain Diamond Wedding Ring, of which the following is a specification, reference being had to the accompanying drawing, forming a part thereof.

Figure 1 is a perspective view of a wedding ring showing my new design; and

Figure 2 is an edge view, partly in perspective, showing one-half of the top band of the ring disclosed in Figure 1.

This ring is composed of three four-leaf clovers at each side of a solitaire diamond center, this center set in a square setting.

Each petal of each four-leaf clover is set with a diamond. Twenty-five diamonds in all.

The entire top of the design (composed of the six four-leaf clovers and the solitaire diamond center) curves over the top of the ring in curvature conforming to the finger, and has open space between each four-leaf clover; a stem from the end clover, at each side, curves down over the shank of the ring, each stem in opposite curvature. The shank is square edge, same width all the way around.

I claim:

The ornamental design for a diamond wedding ring as shown and described.

L LEE PANDRES.
